UNITED STATES PATENT OFFICE.

JAY C. STEESE AND CHESTER A. HOFF, OF AKRON, OHIO, ASSIGNORS TO THE AKRON LAMP COMPANY, OF AKRON, OHIO, A CORPORATION OF OHIO.

LAMP.

Application filed July 23, 1921. Serial No. 486,991.

To all whom it may concern:

Be it known that we, JAY C. STEESE and CHESTER A. HOFF, citizens of the United States, and residents, respectively, of Akron, in the county of Summit and State of Ohio, and Akron, in the county of Summit and State of Ohio, have invented a certain new and useful Improvement in Lamps, of which the following is a full, clear, and exact description.

This invention relates to a lamp structure such as is commonly used in standards of hydro-carbon vapor lamps.

One of the objects of the invention is to provide a structure in which the mixing head and the burners are detachable as a unit from the base portion of the lamp.

Another object is to provide a construction such that the generator tube is fastened to the upright pipe coming from the base or font of the lamp which generator tube will remain in place, after the head and burner of the lamp have been detached and removed. In this condition the generator may be very readily needed or it may be removed as occasion may require.

Reference should be had to the accompanying drawings forming a part of this specification, in which Fig. 1 is an elevation of a lamp embodying the present invention; Fig. 2 is a front elevation of a portion of the lamp wherein the invention resides; Fig. 3 is a side elevation of the showing in Fig. 2; Fig. 4 is a top plan view with portions in section showing co-operating parts of the structure; Fig. 5 is an elevation of a portion of the structure.

Referring to the drawings, 1 indicates the base of the lamp, which is provided with hand engaging portion 2; extending from the base and up through the hand engaging portion 2 is a pipe 3 which is threaded at its end and is adapted to receive a fixture which is indicated at 4. This fixture is threaded at its lower end, as indicated at 5, for engagement with the pipe 3. The fixture 4 is hollow, and has a threaded neck 6 through which extends a valve stem 7 and there is provided a packing nut 8 which engages with the outer threaded portion of the neck 6.

Extending upwardly from the portion 4 is a threaded extension 9. This threaded extension has flat sides such as indicated at 10 and 10^a. Mounted upon the threaded ex-

tension 9 is a thumb nut 11 having a knurled periphery, the nut 11 being movable up or down upon the extension 9.

The interior of the extension 9 is hollow and at its end it is threaded to receive the lower threaded end of a generator tube 12. This generator tube is made of thin walled tubing which is very well known in the art, and the generator is provided with a coiled portion 12^a intermediate its ends which is adapted to be heated by a match or similar heat device, at the starting of the lamp, so as to insure an initial vaporization of the hydrocarbon, for the purpose of starting the lamp.

Co-operating with the portion 9 of the fixture 4 is a bracket 13. This bracket has one portion upon which is mounted a tubular member 14. The opposite portion is provided with a cut out which is indicated at 13^a, this cut out being of sufficient width to be engaged with the flattened sides 10, 10^a of the extension 9, so that when the bracket 13 is assembled with respect to the extension 9, the bracket can not have any appreciable side movement.

Additionally the depth of the slot 13^a is such that when the parts are assembled the opening 13^a is in proper alignment to receive the generator tube.

When the bracket 13 is assembled on the extension 9 the knurled nut 11 is turned down until it engages with the top of the bracket 13, which will securely hold the bracket 13 from being drawn outwardly or against any movement.

In order to provide a more efficient clamping action a portion of the top part of the bracket 13 is recessed, as indicated at 13^b, while on the under side of the nut 11 there is a complementary extension, as indicated at 11^a. When the clamping nut 11 is turned down the extension 11^a seats in the recess 13^b.

At the upper end of the tubular member 14 there is secured a right angle member 15 which is hollow and communicates with a transverse head 16. From the head two tubes 17 and 18 depend, and at their lower end these tubes are provided with collars 17^a, 18^a, which are adapted to receive mantles, such as indicated at 19 in Fig. 1.

These mantles, as will be apparent, are positioned on opposite sides of the generator tube, and when the lamp is in action the

heat from the mantles causes vaporizing of the hydro-carbon which is passing through the generator tube 12.

The member 15 is provided with an opening 15^a which is so positioned that the end of the generator tube 12 may extend through the opening and communicate with the interior of the member 15. The tubular member 14 and the member 14^a serve as air ducts whereby air may pass through these members and mix with the hydrocarbon in gaseous form as it is discharged at the end of the generator tube.

Attention is called to the fact that the bracket 13, the tubular member 14, the member 15, the mixing head 16, and the parts carried thereby, are all secured to each other so as to form substantially a unitary structure. On the other hand, the generator tube 20 is carried by the fixture 4 which is in turn secured to the base portion of the lamp.

When the lamp is assembled and in operative condition if it be desired to remove the generator or if it be desired to needle the same at the end of the generator tube, the same may be accomplished by loosening the thumb nut 11 and the operator grasps the tube 14, giving the same a tilting movement so as to withdraw the bracket 13 from its engagement with the tension, and thereafter elevating the tube 14 and the parts carried thereby. After this has been accomplished, the generator tube may be needled, or removed and a new one inserted in place thereof.

Heretofore it has been the general practice to have the generator tube removable, but usually the generator tube has been held in place at the lower end thereof by some sort of a jamb nut construction. Removing the generator from the remaining structure of the lamp has been a matter of considerable difficulty because the generator tube is so small that the fingers of the manipulator 45 can with difficulty retain it against the side movement, and consequent engagement with the mantles of the lamp which invariably results in breaking of the mantles.

On the other hand, by removing the air tube and the structure associated therewith as in the present instance, the air tube affords an object for the hand of the manipulator to grasp, and it is much easier to manipulate and move the heated structure of the lamp and disassociate it from its engagement with the generator tube than merely removing the generator tube.

Additionally, the construction has considerable advantage in the matter of shipment of a lamp. It is very desirable that the fixture 4 be assembled on the pipe 2 carried in the base of the lamp at the factory so as to insure a tight non-leaking connection, whereas in some prior constructions the air tube and the mixing head and

burners were supported by a bracket which formed an integral part of such fixture, the packaging of the lamp was more or less difficult because of the height of the lamp.

In the present instance the desirable feature of having all the important connections of the lamp made at the factory so that they are gas tight, is accomplished. At the same time the super structure comprising the air tube, the head and the burners is made removable, as is also the generator tube, so that the height of the package required for packing the lamp is materially reduced.

Having described our invention, we claim—

1. In a device of the character described, the combination with a lamp base having an upstanding pipe, a fixture threaded upon said upstanding pipe, a generator tube having one end thereof attached to said fixture, a mixing head, burners carried by said mixing head, an offset member secured to the head and having an opening through which an end of the said generator tube extends, a post secured to the offset member, and a bracket to which the post is secured, said bracket being detachably secured to the said fixture whereby the bracket and the parts carried thereby may be removed as a unit from the said fixture and generator tube.

2. In a device of the character described, the combination with a base having an upstanding pipe, a fixture threaded upon said pipe, a generator tube having one end secured in said fixture, a mixing head, burners carried by said mixing head, an offset member co-operating with the head, an opening through said offset member into which an end of the generator tube extends, an upright member secured to the offset member, a bracket to which the upright member is secured, said bracket having a sliding contact with the said fixture, and means for holding the bracket to the fixture.

3. In a device of the character described, the combination with a base having an upstanding pipe, a fixture threaded upon said pipe, a generator tube having one end secured in said fixture, a mixing head, burners carried by said mixing head, an offset member co-operating with the head, an opening through said offset member into which an end of the generator tube extends, an upright member secured to the offset member, a bracket to which the upright member is secured, said bracket being provided with a recess, said fixture having an extension which is adapted to slidingly engage said recess, and co-operating means upon the walls of the recess and the projection for preventing relative rotation, and means for holding the bracket to the fixture.

4. In a device of the character described, the combination with a base having an upstanding pipe, a fixture threaded upon said

- pipe, a generator tube having one end secured in said fixture, a mixing head, burners carried by said mixing head, an offset member co-operating with the head, an opening 5 through said offset member into which an end of the generator tube extends, an upright member secured to the offset member, a bracket to which the upright member is secured, said bracket having a recess with 10 oppositely disposed flat sides the said fixture having oppositely disposed flat sides and adapted to co-operate with the flat sides of the bracket, and means for holding the bracket and fixture together.
- 15 5. In a device of the character described, the combination with a base having an upstanding pipe, a fixture threaded upon said pipe, a generator tube having one end secured in said fixture, a mixing head, burners 20 carried by said mixing head, an offset member co-operating with the head, an opening through said offset member into which an end of the generator tube extends, an upright member secured to the offset member, 25 a bracket to which the upright member is secured, said bracket having a recess which straddles and engages with the sides of the
- said fixture, and a nut threaded upon said fixture for holding the said bracket and fixture together. 30
6. In a device of the character described, the combination with a base having an upstanding pipe, a fixture threaded upon said pipe, a generator tube having one end secured in said fixture, a mixing head, burners 35 carried by said mixing head, an offset member co-operating with the head, an opening through said offset member into which an end of the generator tube extends, an upright member secured to the offset member, 40 a bracket to which the upright member is secured, said bracket having a recess and the bracket being provided with a groove in the top thereof, said bracket straddling the fixture and engaging with the sides thereof, 45 a nut carried by the fixture, said nut having a flange on the under side thereof which engages a groove in the top of the bracket whereby the bracket and fixture are held to each other. 50

In testimony whereof, we hereunto affix our signatures.
